UNITED STATES PATENT OFFICE.

PERRY E. MACK, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

GAS-ENGINE STARTER.

Application filed June 20, 1921. Serial No. 479,163.

This invention has for its object to provide a convenient means for cranking a gas engine that may readily be attached to the crank shaft and will become automatically disconnected therefrom as soon as the engine turns over on its own power.

With the above and other objects in view, the invention consists in a gas engine starter as herein claimed and all equivalents.

10 Referring to the accompanying drawings in which like characters of reference indicate like parts in different views:

Fig. 1 is an edge view of a gas engine starter constructed in accordance with this 15 invention;

Fig. 2 is a face view thereof;

Fig. 3 is a vertical sectional view on the plane of line 3—3 of Fig. 2; and

20 Fig. 4 is a sectional view on the plane of line 4—4 of Fig. 1.

In these drawings 10 indicates a gas engine crank shaft having a tapered end 11 with oppositely projecting pins 12, as is usual for the attachment of a cranking 25 means.

A drum member 13 has a centrally projecting socket 14 with a tapering bore to fit on the tapering end 11 of the crank shaft and with opposite cam surfaces terminating 30 in hooks 15 for engaging the pins 12 in the manner usual with starting cranks.

The drum proper is contained within a 35 casing or housing formed by a pair of sheet metal shells 16 and 17 with their flanged edges secured together by means of bent over tongues 18 on one engaging in notches 19 in the other. The shell 17 has a bearing on the socket projection 14 against a shoulder of the drum, while the shell 16 has a similar 40 though smaller bearing on a central stud 20 forming an integral projection from the drum.

A clock spring 21 is contained within the 45 drum and is anchored to the stud 20 by having its inner end engaged within a slot 22 through said stud. The outer end of the spring is engaged with a pin 23 riveted to shell 16.

A strap 24 is wound around the drum 50 with its end anchored thereto by means of staples 25 on the opposite sides of projecting rivet heads 26. The free end of the strap passes out of the casing through an elongated tubular eyelet 27 and forms a loop

28 secured by a clip 29 to afford a convenient 55 operating handle portion that remains outside the casing.

In operation the socket 14 is engaged with the pins of the crank shaft and then the strap is pulled by means of the handle loop 60 28, thus causing the drum to turn and rotate the crank shaft in the proper direction for starting the engine. When the engine starts the pins 12 ride out of the hooks 15 65 so that the starter is automatically disconnected. When disconnected, the starter is entirely free from the crank shaft and is supported only by the hand which holds the strap making it possible to use the same 70 starter for any number of engines, as it has no permanent connection with the engine. In drawing the strap out of the casing the spring 21 is wound up so that as soon as the parts are released it turns the drum to rewind the strap thereon in the manner 75 usual with tape measures and the like.

As the strap is being drawn out of the casing for cranking the engine, it holds the casing stationary while the drum is turned to rewind the spring and should the turning of the crank be ineffective for starting the engine the strap is released, permitting the spring to unwind turning the casing to 80 rewind the strap on the drum.

The invention is simple in its construction and, inexpensive to manufacture though it is highly efficient for the purpose intended, and is most suitable for use with fractional horse-power engines that are inconvenient to start with a hand crank. The 85 fact that the starting operation is performed by a mere pull on the strap, in any direction, makes it suitable for use with engines that are so located that they are inaccessible for other cranking means.

What I claim as new and desire to secure by Letters Patent is:

1. A portable self detachable gas engine 90 starter, comprising an engine-shaft-engaging member capable of automatic detachment when the engine starts, a strap wound thereon which on being pulled causes the member to turn, a casing surrounding the member, and spring means connecting the casing and the member for rewinding the strap by 95 turning the casing.

2. A self detachable gas engine starter comprising a drum having a gas engine- 100

- shaft-engaging socket, a casing rotatably mounted on and surrounding the drum, a strap secured to the drum and wound thereon, and a clock spring within the drum and connected to the drum and to the casing for turning the casing to rewind the strap.
3. A gas engine starter comprising a cylindrical casing formed of flanged disk-like sections with their flanged edges secured together, a drum member within the casing with a shouldered central stud having bearing in one casing section and a projecting engine-shaft-engaging socket member having a bearing in the other casing section, a clock spring within the drum and connected therewith by having its inner end engaged with the stud, a pin secured to one of the casing sections and projecting into the drum and having the outer end of the spring connected thereto, and a strap attached to the drum and wound thereon and passing out through an opening in the casing by pulling which the drum may be turned for turning the engine shaft.
- 25 4. A gas engine starter comprising a cylindrical casing formed of disk-like flanged concave sections secured together at their flanged edges by having tongues of one bent over in notches of the other, a drum within the casing, having a shouldered central stud fitting in an opening of one casing section and a shouldered projection fitting in an opening of the other casing section, said projection forming an engine-shaft-engaging member, a clock spring within the drum with its inner end anchored to the stud by fitting in a slot thereof, a pin secured to a casing section and connected with the outer end of the spring, a strap secured to the drum and wound thereon and passing out through an opening formed in the casing sections, and a tubular eyelet fitting in said opening and through which the strap passes.
- 40 5. In a gas engine starter, a drum having means for connection with an engine shaft, a strap wound thereon, and means for connecting the strap with the drum, comprising a pair of staples on the drum through which the end of the strap is passed and rivets in the drum between the staples with their heads projecting from the drum to cause the strap to bend between the staples.
6. A hand-attached self detachable starter for gas-engines comprising an engine-shaft-engaging member having releasable engaging parts by means of which it may be supported by the shaft, a strap wound on said member which on being pulled causes the member to turn and so turn the shaft, a casing rotatably mounted on and supported by and enclosing the member, and spring means connecting the member and the casing for rewinding the strap.
7. A hand tool for starting gas engines comprising an attachable engine-shaft-engaging member having means for engaging an engine shaft until the engine is started and then effecting its disengagement, said means when engaged being supported solely by the engine shaft, a strap wound on said member which on being pulled causes the member to turn and turn with it the engine shaft, a casing surrounding the member and rotatably mounted thereon to permit relative rotary movement, and a clock spring connected at one end to said member and at the other end with the casing, said strap passing through an opening in the casing.
8. In a gas engine starter, the combination with the crank shaft of a gas engine provided with a tapered end with lateral engaging pins, of a drum member having a tapered socket to fit upon the tapered end of the crank shaft for supporting the drum and having hooks for engaging the pins, a strap attached to the drum and wound thereon and adapted to turn the drum for cranking the engine when pulled from the drum, a housing surrounding the drum and having the strap pass therethrough, and a coil spring connected with the drum and with the housing for rewinding the strap on the drum.

In testimony whereof, I affix my signature:

PERRY E. MACK.
